UNITED STATES PATENT OFFICE.

JAMES W. STUART, OF MACOMB, ILLINOIS.

DESIGN FOR A FRAME FOR POWER-HAMMERS.

SPECIFICATION forming part of Design No. 33,423, dated October 23, 1900.

Application filed May 10, 1900. Serial No. 16,238. Term of patent 7 years.

To all whom it may concern:

Be it known that I, JAMES W. STUART, a citizen of the United States, residing at Macomb, in the county of McDonough, State of Illinois, have invented and produced a new and original Design for a Frame for Power-Hammers, of which the following is a specification, reference being had to the accompanying drawing, forming part thereof.

- o As shown in the drawing, the leading or material feature of my design consists of the base *a*. Extending horizontally and parallel with each other are two parts *b b*, united by cross-ties *c c c*. United at one end of base *a* and extending upward is an oblong block *d*. United at upper end of block *d* is a T-shaped block *e*, the upper surface of which is a transverse groove. United at upper surface of

block *e* is an oblong block *f*. Near rear of base *a* and extending upward and parallel with each other are two posts *g g*, united by cross-ties *h h h h*. Near the upper end of and united to posts *g g* and extending to near base *a* and united to block *d* are two braces *i i*.

Having described my invention, what I claim as new, and desire to secure by Letters Patent, is—

The design for a frame for a "power-hammer" as herein shown and described.

In testimony whereof I have signed my name to this specification in the presence of two subscribing witnesses.

JAMES W. STUART.

Witnesses:

PHILIP E. ELTING,
MARY I. CHANDLER.
